UNITED STATES PATENT OFFICE.

JAMES N. HERSH, OF ALLENTOWN, ASSIGNOR TO HIMSELF, AND WILLIAM R. BUTLER, OF MAUCH CHUNK, PENNSYLVANIA.

HEATING-FURNACE.

SPECIFICATION forming part of Letters Patent No. 460,811, dated October 6, 1891.

Application filed February 16, 1891. Serial No. 381,632. (No model.)

To all whom it may concern:

Be it known that I, JAMES N. HERSH, a citizen of the United States, and a resident of Allentown, Lehigh county, Pennsylvania, 5 have invented certain Improvements in Heating-Furnaces, of which the following is a specification.

The object of my invention is to provide a simple and economical form of circulating 10 device for the products of combustion in a hot-air furnace; and this object I attain in the manner hereinafter set forth, reference being had to the accompanying drawings, in which—

15 Figure 1 is a vertical section of a heating-furnace constructed in accordance with my invention. Figs. 2 and 3 are transverse sections, respectively, on the lines 1 2 and 3 4, Fig. 1. Fig. 4 is a sectional plan view on the 20 line 5 6, Fig. 1, and Fig. 5 is a sectional plan view on the line 7 8, Fig. 1.

A is the outer casing of the furnace, mounted upon a suitable base A', upon which is also mounted the ash-pit casing B, which supports the fire-pot D, and above the latter is mounted the combustion-chamber F, closed at the top by a dome-like cap or cover F'. With the fire-pot communicates the feed chute or hopper G, which is provided with a 25 suitable door G', and at the rear of the fire-pot is the outlet-flue H, direct access to which from the combustion-chamber can be prevented by means of the damper a. The outlet-flue H also communicates through a de- 30 pending pipe H' and elbow-neck I with the ash-pit of the furnace, this communication being cut off, when desired, by means of the damper b, the pipe H', and neck I, forming the usual dust-flue.

40 Mounted in the upper portion of the hot-air chamber within the casing A is an annular drum J, consisting of inner and outer rings d, applied to annular flanged top and bottom plates f and g, and this annular drum is supported upon pipes M' N' and M' N', the pipes M' N' projecting upward from suitable necks i, formed at the opposite sides of the feed-chute G, and the pipes M' N' being applied to similar necks m, formed at the opposite sides of the dis- 45 charge-flue H. Depending from the annular drum J, on opposite sides of the combustion-

chamber casing F, are pipes M² M³ and N² N³, each pair of pipes being connected at the bottom by a return-bend P, and in the drum J, between the pipes M² M³ and between the pipes N² N³, are transverse partitions h, which thus divide said drum into front and rear chambers, the front chamber communicating with the pipes M' M² and N' N² and the rear chamber communicating with the pipes M³ M⁴ and N³ N⁴. When the damper a is closed, therefore, the products of combustion are compelled to take the course indicated by the arrows in Fig. 1—that is to say, they rise through the pipes M' N', traverse the front half of the drum J, descend through the pipes M² N², pass through the return-bends P, ascend to pipes M³ N³, traverse the rear half of the drum J, and descend through the pipes M⁴ N⁴ to the discharge-flue H. By 55 this means an extended circulation of the products of combustion is insured throughout all portions of the air-heating structure of the furnace, and a great portion of this circulation is downward or in opposition to 60 the natural rising tendency of the heated products of combustion. Hence said products cannot traverse the pipes and passages so rapidly as to escape before their heat has been thoroughly utilized.

70 The construction of the circulating device is also of a simple and inexpensive character, said circulating device being composed mainly of pipe-sections, which can be readily fitted to the necks of the feed-chute, discharge-flue, and connecting-drum.

75 I am aware that air-heating furnaces have been provided with upper and lower drums connected by pipes, some of which form ascending flues and others descending flues, and hence I do not claim such broad construction; but

80 I claim as my invention and desire to secure by Letters Patent—

85 The combination of the fire-pot having a feed-chute at the front and a discharge-flue at the rear, a closed combustion-chamber casing mounted on said fire-pot, an annular drum located in the upper portion of the air-heating chamber and divided by transverse partitions 90 into front and rear chambers, ascending flues connecting the front chamber of said drum 95

with the feed-chute at the front of the fire-pot, descending flues connecting the rear chamber of the drum with the discharge-flue at the rear of the fire-pot, and descending and ascending flues arranged in pairs on opposite sides of the fire-pot, the flues of each pair being connected at the bottom and one flue of each pair communicating at the top with the front chamber of the annular drum and the

other with the rear chamber of the same, substantially as specified.

In testimony whereof I have signed my name to this specification in the presence of two subscribing witnesses.

JAMES N. HERSH.
